UNITED STATES PATENT OFFICE.

MORITZ SCHENKEL, OF CHARLOTTENBURG, NEAR BERLIN, GERMANY, ASSIGNOR TO
SIEMENS-SCHUCKERT-WERKE G. M. B. H., OF BERLIN, GERMANY, A CORPORATION
OF GERMANY.

ANODE FOR ELECTRIC VACUUM APPARATUS.

1,326,972.

Specification of Letters Patent.

Patented Jan. 6, 1920.

Application filed September 13, 1916. Serial No. 119,883.

To all whom it may concern:

Be it known that I, MORITZ SCHENKEL, a German citizen, and resident of Charlottenburg, near Berlin, Germany, have invented 5 certain new and useful Improvements in Anodes for Electric Vacuum Apparatus, of which the following is a specification.

My invention relates to electric vacuum apparatus and more especially to anodes for 10 use in apparatus of this class such as mercury vapor rectifiers.

In a prior application for patent of the United States filed by Joseph Just and myself, Ser. No. 114,644, relating to electric 15 vacuum apparatus an annular anode of this class was described and claimed. The present invention contemplates providing an annular anode which is built up from a number of annular sections some of these sections being anodes and the rest being partitions 20 adapted to separate these sectional anodes from each other; the whole forming a self-contained anode body adapted to be easily put in place and to be removed from 25 the vacuum vessel as a whole.

In the drawings accompanying the specification and forming part thereof,

Figure 1, shows the preferred form of an anode according to my invention as applied 30 to a mercury vapor rectifier, the figure showing one half of said rectifier and anode in vertical section.

Fig. 2, shows a modification of the anode structure.

Fig. 3, shows a further modification thereof.

Referring to Fig. 1 of the drawings 1 is the rectifier vessel, 2 is its cover, 3 is a seal securing an airtight fit between the vessel 40 and cover. 5, 6, 7 are three annular anodes, 8 is a conductor adapted to conduct the electric current to said anodes and to feed a cooling medium such as water into channels provided to this end within said anodes. In 45 the case where the individual anode rings present different phases, a number of current conductors corresponding to the number of different phases should be provided and connected with the respective anodes. 50 9 is a seal interposed between the cover opening and the conductor passing through it. 20 is a mercury cathode which might however be replaced by a cathode of any other suitable kind such as for instance 55 a glow cathode of a suitable form.

10, 11, 12, 13 are partitions made of a heat resisting insulating material such as porcelain, these same partitions being interposed between the anodes as well as between the lower and upper anode and the plates 14 and 15 respectively which tend to press the partitions and anodes tightly together under the action of screw bolts such as 16. By aid of these pressure plates and bolts the anode rings and partitions are made to form a 60 compact self-sustaining body adapted to be removed from the rectifier vessel as a whole after the cover 2 has been removed.

The periphery of the lower pressure plate 14 rests on a shoulder 17 provided within the rectifier vessel, said shoulder preferably serving to render the chamber formed below said pressure plate tight so that in the case, where the upper partition 13 has the form of a solid plate, the space left between said 70 plate 13 and the cover 2 of the vessel forms a separate chamber not connected with the vapor chamber proper and adapted to be used as a preliminary vacuum chamber.

As shown in the drawings the partitions 80 11 and 12 as well as the lowermost partition 10 may be bent or curved downward or else their center part may carry metal cylinders 10^a, 10^b, such cylinders being preferably inserted in annular grooves 18, 19 of said partitions such as shown in Fig. 2. In the case where annular anodes of a different diameter are employed, the whole anode assumes the form of a cone, the diameter of the annular anodes or rings increasing either in 85 one or the other direction. This is also illustrated in Fig. 2.

So far as the scope of the invention goes, it is of course, also possible instead of placing the faces of the anodes which are struck 95 by the arc, on the inner side of the anode rings, to place them so that they are facing outwardly. This modification is shown in Fig. 3, where annular anodes 5^a, 6^a, 7^a are inserted between the bell-shaped partitions 10^a, 11^a, 12^a and 13^a, the entire system being held together with the aid of ring plates 14^a, 15^a and by screw bolts 16, placed in this case on the inside of the anode ring. The conductor 8 in this case is also placed and 100 connected to the anode at the inside of the ring as shown in Fig. 3.

I claim:—

1. An anode for electric vacuum apparatus composed of a plurality of anode rings 110

- and at least one partition separating said rings from each other.
2. An anode for electric vacuum apparatus composed of a plurality of superposed 5 anode rings and at least one partition separating said rings from each other.
3. An anode for electric vacuum apparatus composed of a plurality of anode rings and at least one annular partition 10 separating said rings from each other.
4. An anode for electric vacuum apparatus composed of a plurality of solid annular anodes and annular partitions arranged between each two adjacent anode rings.
- 15 5. An anode for electric vacuum apparatus composed of a plurality of solid annular anodes and annular insulating partitions arranged between each two adjacent anode rings.
- 20 6. Anode for electric vacuum apparatus, composed of a plurality of anode rings of equal diameter and at least one partition separating said rings.
7. In electric vacuum apparatus, in combination a vacuum vessel and a self-sustaining 25 anode body of substantially cylindrical
- shape, composed of a plurality of individually active anode elements and disposed within said vessel.
8. In electric vacuum apparatus, in combination a vacuum vessel and a self-sustaining anode body of substantially cylindrical shape, composed of a plurality of individually active anode elements removably arranged within said vessel. 30
9. In electric vacuum apparatus, in combination a vacuum vessel and a plurality of annular anodes and of partitions between said anodes removably arranged within said vessel. 35
10. A self-sustaining anode body, comprising in combination a plurality of solid annular anodes and partitions alternately disposed one above the other and means for holding said anodes and partitions together. 40
11. A self-sustaining anode body, comprising in combination a plurality of solid annular anodes and bell-shaped partitions alternately disposed one above the other and means for holding said anodes and said partitions together. 45

MORITZ SCHENKEL.
